CLAIM

The ornamental design for a component for electronic devices, as shown and described.

DESCRIPTION

FIG. 1 is a perspective view of the invention from the front left side.

FIG. 2 is a perspective view from the rear right side thereof.

FIG. 3 is a left elevation view thereof.

FIG. 4 is a right elevation view thereof.

FIG. 5 is a rear elevation view thereof; and,

FIG. 6 is a top elevation view thereof.

The broken lines in the drawings are employed to show environmental structures only, and form no part of the claimed design.
